W. WESTBURY.
CYLINDER CAPPING DEVICE.
FILED OCT. 13, 1921.

Inventor

William Westbury

By G. C. Hines

Attorney

UNITED STATES PATENT OFFICE.

WILLIAM WESTBURY, OF CANEY, KANSAS.

CYLINDER-CAPPING DEVICE.

Application filed October 13, 1921. Serial No. 507,404.

To all whom it may concern:

Be it known that I, WILLIAM WESTBURY, a citizen of the United States, residing at Caney, in the county of Montgomery and 5 State of Kansas, have invented new and useful Improvements in Cylinder-Capping Devices, of which the following is a specification.

This invention relates to an electrical capping device for use in severing glass cylinders into suitable lengths preparatory to opening and flattening the cylinder sections for the production of window glass. More especially the invention relates to a capping 15 device of that kind employing an electrically heated cracking wire which is passed around the cylinder at the point where the cylinder is to be cut.

One object of the invention is to provide a simple, inexpensive and efficient type 20 of device of this character which may be readily and conveniently applied for use and which is adapted for use in connection with cylinders of different diameters.

25 A further object of the invention is to provide a capping device whereby the heat may be applied as required to thick and thin portions of a cylinder, thereby preventing the fractures and waste caused in the use of 30 ordinary capping devices wherein the heat is uniformly transmitted by the cracking wire without regard to the relative thickness of portions of the part of the cylinder encompassed thereby.

35 The invention consists of the features of construction, combination and arrangement of parts, hereinafter fully described and claimed, reference being had to the accompanying drawing, in which:—

40 Figure 1 is a side elevation of a portion of a capping horse and a portion of a glass cylinder resting therein, showing the application of the invention.

45 Figure 2 is a cross sectional view thereof, showing the device as arranged for use, and also showing the circuit closing element.

50 Figure 3 is a longitudinal section through the socket and a side elevation of the shank portion of the capping stick adapted to fit therein.

55 Figure 4 is a perspective view of the adjustable nose piece or conductor on the stick.

Figure 5 is a detail section on line 5—5 55 of Figure 4, showing the arrangement of

the crossed ends of the applied cracking wire.

Referring now more particularly to the drawing, 1 represents in general a capping horse of any ordinary or approved construction, that shown in the present instance being provided with suitably arranged and spaced saddles 2 to receive the glass cylinder 3 which rests therein. Properly mounted at one side of the capping horse is a rod or bar 4, which is arranged at one side of the capping horse above the level of the saddles and extends parallel with the cylinder 3.

The capping device comprises a socket 70 member 5 made of fiber or any other suitable electric insulating material, and having contained therein a contact spring 6 of brass or other suitable material, with which is connected one of the electric conductors 75 or feed wires 7. This socket member 5 is supported upon the rod or bar 4 by means of a two-part clamp 8, the parts of which are adjustably and detachably connected by means of a screw or bolt 9, whereby 80 the socket piece may be fixed in position or loosened for removal or adjustment as occasion may require. A single socket piece of this character may be provided and adjusted longitudinally along the 85 rod or bar 4 to any point along the length of the cylinder where the cut is to be made; or a series of such socket pieces, suitably spaced apart, may be provided for the application of the cracking device at 90 proper points along the length of the cylinder.

A capping stick is provided for detachable connection with the socket piece and consists of a head portion 10, a shank portion 11 and an arm 12 connecting said head and shank portions. The head and shank portions are preferably made of fiber or some other suitable electric non-conducting material, while the arm 12 may be composed of a bar of metal of proper kind and thickness to give the necessary strength and rigidity. The shank portion 11 is of a form to fit within the socket piece 5 and is provided with a stop or abutment 13 to 100 limit its inserting movement. The shank portion 11 carries a spring metal contact 14 for engagement with the contact 6 in the socket piece 5 when said parts are fitted together.

Carried by the head piece 10 is an adjustable nose piece or conductor 15, said nose piece or conductor being made of a good conducting material and of substantially elbow form. Said nose piece 15 is pivotally mounted, as at 16, at the angle of intersection of its arms 17 and 18 upon the head piece 10, and the arm 17 thereof is connected with the spring contact 14 by a conducting wire 19, whereby when the capping stick is fitted in the socket member the nose piece or conductor 15 will be electrically connected with the feed wire 7 forming one side of the electric circuit.

15 The arm 17 of the nose piece 15 is comparatively broad and provided with an arcuate slot 20 through which passes a clamping screw or bolt 21 carried by the head piece 10, whereby said nose piece or conductor 15 is adjustably mounted on the head piece 10 so that its arm 18 may be disposed at different working angles to adapt the cracking wire 22 to be properly disposed and passed around glass cylinders varying in diameter, thus making the device applicable, without adjustment of the capping stick per se, to different diameters of cylinders. As shown, the cracking wire 22, which is made of high resistance metal, is secured at one 30 end 23 to the arm 18 of the nose piece or conductor 15, and said wire is thence passed for use once around the cylinder 3 so that its opposite end 24 will extend beyond or across the end 23. The end 24 of the arm 35 thence passes around a pulley or other guide member 25 carried by a coiled spring 26 secured to the shank 11 and is finally fastened in any removable manner to the head portion 10, as by means of a clamp screw or other suitable fastening device 27. The portion 40 24 of the wire is thus looped or guided for running connection with the guide 25 and is adapted to be drawn upon by the spring 26, the parts 25 and 26 serving as an automatic take-up device for taking up any slack in the wire 22 which may occur after the wire is applied and the current turned on, such slack commonly occurring as a result of the expansion of the wire. A 45 circuit closing device 28 is provided for completing the circuit for causing the electric current to pass entirely through the wire 22 or through a determined portion thereof. This circuit closing device 28 consists of a fiber or other non-conducting block, properly shaped so that it may be easily held in the hand of the operator, said block having spaced circuit contacts adapted to be connected by a snap switch 29 whereby 50 the current may be turned on and off. One of said contacts is connected with a second feed wire 30, while the other contact is connected with a contact point 31.

55 It will be observed that the arm 18 of the conductor 15 is provided with an insulated

covering 32 against which the end 24 of the cracking wire 22 bears at the point where it crosses the end 23 of said wire, the said ends 23 and 24 of the cracking wire being thus insulated from each other. The end 70 23 of the wire being connected with the conductor 15, which is connected with the feed wire 7, it will be evident that when the contact point 31 of the circuit closing device 28 is brought into contact with the end 24 of the wire 22, and the switch 29 is turned on, an electric circuit will be completed entirely through the wire 22, whereby said wire will be heated throughout. In such operation it will be apparent that the 80 entire circumference of the cylinder, at the point where it is encompassed by the wire 22, will be heated for the cracking operation. The construction described, however, adapts the device for use in heating only 85 a portion of the wire, and consequently a portion of the cylinder, so that a thick part of the cylinder may be initially heated before the current is fully applied around the cylinder. Thus the contact point 31 may 90 be applied at any point around the wire 22, in which event the current will pass only through that portion of the wire through which the current is applied between the conductor 15 and the contact point 31, thus 95 enabling a thick portion of a cylinder to be heated before a comparatively thinner part is heated. It frequently happens that the glass of the cylinder is uneven in thickness, the cylinder being thicker at one side at the 100 point to be cracked than it is at the other side. If, under such conditions, the cylinder is heated to the same intensity all around, the thin part will be heated sufficiently for cracking, but the thick will 105 not be heated sufficiently to break clean, while if the thick part of the cylinder is heated sufficiently for a clean break the thin part will be burnt, causing checks or flaws therein. By means of my device, these 110 objections may be avoided, as the thick part of the cylinder may first be heated to a preliminary extent while the thin part remains unheated, and then the current may be turned fully on throughout the whole of the 115 wire to heat the cylinder all the way around, thus heating both the thick and thin parts to the exact degree required to secure a clean break all around the cylinder.

It will be understood, of course, that but a 120 single socket piece need be employed for use in conjunction with a detachable capping stick for severing any length of cylinder at proper points along its length, since the socket piece is adjustable on the rod or bar 125 for lengthwise movement of the cylinder, but it is also to be understood that a series of socket pieces arranged at desired distances apart and adjustable to vary their distances apart, may be employed for use in 130

conjunction with one or more removable capping sticks, so that one or more cracking operations may be carried out on one cylinder at one and the same time, or the cracking device properly disposed or adjusted for use as convenience or occasion may require.

Having thus fully described my invention, I claim:—

1. A cylinder cracking device comprising a wire band adapted to be passed around the cylinder, and means for passing an electric heating current through any predetermined portion of the length of said band.
2. A cylinder cracking device comprising a wire band adapted to be passed around the cylinder, the ends of said band being electrically separated, and one end of the band being connected with one side of an electric circuit, and a movable circuit closing device operable for contact with the other end of the band or with the band at any point between the end of the band connected with one side of the electric circuit and the opposite end of said band.
3. A cylinder cracking device comprising a wire band adapted to be passed around a cylinder, one end of the band being normally connected with one side of an electric circuit, and means connected with the other side of the electric circuit and adapted for electrical contact with any portion of the band.
4. A cylinder cracking device comprising supporting means, a cracking wire carried thereby and adapted to be extended around a glass cylinder, an electric circuit including one end of the wire, and circuit closing means for completing the circuit through the wire at any point in the length of said wire.
5. A cylinder cracking device comprising a heating wire adapted to embrace the cylinder, a support, means carried by said support for connecting one end of said wire with one side of an electric circuit, and circuit closing means connected with the other side of the electric circuit and adapted for contact with any portion of the wire between its ends.
6. In a cylinder cracking device, a capping stick, a heating wire adapted to be passed around the cylinder, an adjustable conductor on the capping stick having an

arm to which one end of the wire is electrically connected, means connecting said conductor with one side of an electric circuit, and a circuit closing device connected with the other side of the electric circuit and adapted for contact with any portion of the cracking wire.

7. A cylinder cracking device comprising a capping stick, a cracking wire adapted to embrace the cylinder, an adjustable elbow-shaped conductor carried by the capping stick, and with which one end of the wire is electrically connected, means connecting said conductor with one side of an electric circuit, and a hand manipulated circuit closing device connected with the other side of the electric circuit and adapted for contact with any portion of the cracking wire for passing a circuit entirely therethrough or through a portion thereof.

8. A cylinder cracking device comprising a cylinder supporting horse, a socket mounted on said horse and provided with a contact connected with one main conductor of an electric circuit, a stick having a shank portion provided with a cooperating contact adapted to fit within said socket member, an adjustable conductor of elbow-form upon the stick in electrical connection with the contact thereof, said conductor having an arm projecting beyond the stick, a cracking wire adapted to be passed around the cylinder and having an end portion connected with said arm and adapted to have its opposite end portion secured to the stick out of electrical contact with the first-named end, and a circuit closing device connected with the other side of the electric circuit and having a controlling switch and adapted to be engaged with the cracking wire at any point between the ends thereof.

9. In a cylinder cracking device, the combination of a cracking wire, an electric circuit with one side of which one end of the wire is connected, and a contact connected with the other side of the electric circuit and operative for circuit closing connection with any portion of the wire.

In testimony whereof I affix my signature.

WILLIAM WESTBURY.
